UNITED STATES PATENT OFFICE

OTTO SCHÄFERER, OF BASEL, SWITZERLAND

AUTOMATIC LATHE

Application filed July 9, 1931, Serial No. 549,734, and in Switzerland August 8, 1930.

The invention relates to a multi-spindle machine of the vertical type for machining solid or hollow material in lengths into short work pieces, the lengths of material being presented to the tools by vertically arranged spindles. It is characterized by the feature that the hollow work piece spindles provided with means to grip and feed forward the material automatically and carried by a revolver drum are rotated upon their own axes at such a speed that the work pieces within them set themselves accurately centrally owing to centripetal force so that the known chattering movements of the lengths of material are avoided.

In this type of machine with work piece spindles rotating on their own axes a separate control for the forward feed of the material is necessary, which must be so arranged that no interference with the rotation of the spindle is caused thereby. This control is effected in the manner described below by separate mechanism lying outside the path of rotation of the spindles.

The drawings show by way of example an embodiment of the invention in which operation upon rod form material by means of vertically and horizontally fed tools is adopted.

Figure 1 shows the whole machine in front view.

Figure 2 is a plan thereof.

Figure 3 shows in plan certain of the parts arranged on the pedestal.

Figure 4 is a horizontal section on the line A—B of Figure 1.

Figure 5 is a vertical section of the machine taken on two different planes and drawn to a larger scale.

Figures 6, 7, 8, 9, 10 and 10a illustrate details of the machine.

Figure 11 shows one of the work pieces which can be produced by the machine, and

Figure 12 shows a detail modification.

Figure 13 represents in vertical section a further modification.

Figure 14 is a corresponding horizontal section thereof.

On the pedestal 1 (Figures 1 and 5) is mounted an electric motor 2 which through

a safety coupling 2a, a horizontal shaft 3, a change speed gear 3a, a countershaft 4 and bevel gears 5, 6 drives the vertical main shaft 7. The latter drives through a gear wheel 8 a set of vertical spindles 10 rotating on their own axes, arranged to hold the work pieces in form of rods and carried in a vertical revolver drum 9 so that they can be moved from one working station to the next, the spindles being provided with small wheels 10a meshing with the greater common driving wheel 8 whereby they are rotated upon their axes at high speed, this speed depending on the kind of the material of the work pieces and on the diameter thereof. The shaft 3 drives through a chain another shaft 11 which through a worm 11a (Figure 3) and a worm wheel 12a drives an auxiliary control shaft 12, and through a worm 11b a worm wheel 14 with a toothed coupling head 15 mounted loose upon a counter-shaft 13. On the shaft 12 is a cam 16 with which coacts a roller on a clutch disengaging lever 17. On the shaft 13 is slidably keyed a toothed coupling 18 which under the action of a helical spring normally engages with the coupling head 15 to drive the shaft 13 from the worm wheel 14. This drive can be interrupted by sliding of the coupling sleeve 18 effected from the auxiliary control shaft 12 during its rotation by the cam 16 and the clutch lever 17.

The counter-shaft 13 is in driving connection through a change speed gear 19 with a shaft 21 on which a toothed coupling sleeve 22 is slidably keyed. Opposite the sleeve 22 a coupling sleeve 23 carrying a bevel wheel 24 is mounted loose upon the shaft and runs in a wide bearing 25. The sleeve 22 can be coupled and uncoupled by a hand lever 26 and fork 27.

Beneath the shaft 21 lies an auxiliary shaft 28 which at one end carries a toothed wheel 28a which meshes with a toothed wheel 28b (Figure 1) on the coupling sleeve 23, and at the other end is provided with a hand crank 29 by which if necessary the coupling sleeve 23 can be rotated by hand. The bevel wheel 24 which can be rotated automatically

from the shaft 21 or by hand through the shaft 28, meshes with a bevel wheel 30 (Figures 4 and 5) which is mounted on a radially directed shaft 31. This shaft 31 and two further radially directed shafts 34, 35 form the feed shafts uniformly distributed around the axis of the machine, for the various tools, which here, corresponding with the number of work spindles 10, are provided in six pairs, each pair comprising a vertically working tool and a horizontally working tool. The tool feed shaft 31 carries a bevel wheel 31^a which meshes with a wheel 33 loosely mounted on the vertical main shaft 7 and borne in the oil tray 36. Wheels 34^a, 35^a on the other tool feed shafts 34, 35 mesh with this wheel 33 (Figure 4).

The tool feed shafts 31, 34, 35 carry at their outer ends the bevel wheels 31^b, 34^b and 35^b, respectively, for driving bevel wheels 31^c, 34^c and 35^c. These are each fast upon respective counter-shafts 32 which are borne in brackets on the oil tray 36 and upon each of which are secured four cams 37, 38, 37^a, 38^a.

With these latter respectively coat the follower rollers of lifting arms 40, 41, 40^a, 41^a pivoted on the oil tray 36. Each lifting arm is provided with an adjustably arranged pivot block 42 and to these blocks are pivoted rods 42^a, 42^b, 42^c and 42^d. These are connected to swinging levers 43^a, 43^b, 43^c and 43^d respectively by which the vertical and horizontal tool carriers 43 and 44 receive their feed. These levers are rockably arranged on pillars 45 in such a manner that they are adjustable in height. The pillars 45 which are screwed into a centre piece in the oil tray 36 forming the machine base, carry an adjustably secured guide member 46 which receives the vertical tool carriers 43. The horizontal tool carriers 44 in which the tools are adjustable are adjustably arranged on the pillars 45 above the guide member 46 for the vertical tool carriers.

Above the tool carriers is a bearing member 47 which may be termed the spindle headstock which is firmly secured to the pillars 45 and forms a bearing for the revolver drum 9. The drum 9 carried in this headstock 47 is recessed in the centre as can be seen in Figure 5 and provided at the top and bottom with roller bearings for the vertical work spindles 10.

At the top it is provided with an indexing plate 48 of greater diameter than the drum 9 and borne with the latter is the headstock 47 easily rotatable on a ball thrust bearing 49. The indexing plate 48 serves for step by step rotation of the revolver drum 9 and for holding the latter stationary in its working positions. In the periphery of the indexing plate 48 six recesses 50 are provided in which a bolt 51 (Figure 2) periodically engages, which is toothed on one longitudi-

nal side to mesh with a segment 51^a which is pivoted at 51^b to swing in the horizontal plane and is under the control of a lever 51^c provided with a follower roller which coats with a cam 51^d upon the auxiliary control shaft 12. The indexing plate 48 also has slots 52 cut therein Maltese cross fashion, by which a pin 53 on a lever 54 can step the indexing plate forward. The lever 54 is fast upon a short control shaft 55, borne vertically in the headstock 47, carrying a toothed wheel 57 meshing with a wheel 56 (Figure 5) on the auxiliary control shaft 12 and thus intermittently rotated thereby to effect the movement of the indexing plate 80

A grooved cam drum 58 is fast on the control shaft 55 above the lever 54. This drum is surrounded by a control sleeve 59 with a lifting piece 60 held therein, which sleeve is provided with a cam follower 61 engaging in the groove of the drum 58, so that during the rotation of the drum 58 it is alternately raised and lowered while by engaging over a pin 62 carried by an arm 63 (Figure 1 and 2) rotation of the sleeve is prevented.

On the control shaft 55 there is also a cam control mechanism 64 for periodically operating a swinging member forming a stop for the material fed forward for a new working operation, this stop being longitudinally adjustable on its toothed shaft 66 and the latter being removable from its bearing in the tool guide member 46.

Each work spindle comprises a tube 72 (Figure 6) upon which the toothed wheel 10^a driven by the wheel 8 on the main shaft 7 is fastened, while a slotted sleeve 69 is adjustably secured thereon. On the sleeve 69 is a sliding sleeve 68 provided with a peripheral groove 68^a. In the slots of the sleeve 69 and within the sliding sleeve 68, swinging lifting levers 70 (Figures 6 and 7) are provided which are suspended on an annular seat 73 and also bear against a sleeve 74 (Figure 6) secured to the upper end of the work piece gripping tube 71. The sliding sleeve 68 actuates the lifting levers 70 when its groove 68^a comes into cooperation with the lifting piece 60 of the control sleeve 59 and is then moved vertically thereby. When in this control operation the sliding sleeve 68 is moved downward, a hollow in the sleeve 68 permits the lifting levers 70 to swing outwards under centrifugal force (see Figure 5 right hand side), while when the sleeve 68 is raised they are moved inwards thus exerting a lift on the sleeve 74 to move the work piece gripping tube 71 and the parts carried thereby into the working position as described below.

In bores in the top of the sleeve 74 are provided positioning pins 75 which bear at one end against the tube 72 and at the other

against a ring 77 located in a sleeve 76. The sleeve 76 can be secured to the sleeve 74 by an adjusting screw. The ring 77 has two inwardly directed slots 77^a which serve as 5 guides for inwardly sliding brake shoes 78. The shoes 78 which act to brake the material when it is fed forward, are exchangeable so that with thinner or thicker material they can be replaced by others of appropriate size. A spring spreading ring 78^a 10 between the brake shoes 78 serves to prevent them from falling out of the ring 77, when there is no length of material in the work spindle.

15 The lower end of the work gripping tube 71 is attached to a split collet 79 (Figure 6) which at the outer side has a conical head 79^a which is drawn into a seat 72^a in the tube 72 to close the collet, so that in the 20 working condition the spring limbs of the collet 79 grip the work piece or rod z and the latter is thus held in the work spindle and rotates with it. The release of the collet 79 is effected by lowering of the sliding 25 sleeve 68 (when a work spindle 10 is in engagement with the control sleeve 59), which allows the lifting levers 70 to swing outwards and in consequence the sleeve 74 with the tube 71 resting on their edge 70^a can 30 sink slightly thus releasing the head 79^a of the collet 79 from the seat 72^a of the tube 72 so that the length of material can descend by its own weight for a further sequence of operations.

35 A sudden jolt in the movement of the descending material is prevented by the braking action of the shoes 78, the latter following the movement of the material sliding down on the inner inclined surfaces 77^b of the ring 77 and thus bearing against the material.

It remains to describe the mechanism for periodically actuating the auxiliary control shaft 12. As above stated the shaft 11 is 45 driven from the shaft 3 by the worm 11^a (Figure 3) which transmits motion to the worm wheel 12^a. The latter is mounted together with one half of a toothed coupling 80 (Figure 10) loose on a bearing bush 81 50 arranged on the machine frame and in which the auxiliary control shaft 12 rotates. On the shaft 12 is slidably keyed the other half 80^a of the coupling, provided with a lifting surface 80^b and stop lug 80^c, which is under 55 the pressure of springs 80^d. A spring actuated bolt 81 engages beneath the lifting surface 80^b of the coupling half 80^c where it bears against the lug 80^c and thus prevents the engagement of the coupling half 80^a under the action of the springs 80^d. The 60 bolt 81 is provided with a follower roller 81^a which under the action of the bolt spring 81^b is pressed against an inclined surface 82^a (Figure 3) of a slider 82 guided to move 65 in a straight line path. This slider is under

the action of springs 85 and at its outer end has a handle 84. At the inner end it is provided with a bevelled nose 82^b (Figure 9) which coacts with a cam 33^a on the bevel wheel 33 (Figure 5).

When this cam 33^a during the periodic rotation of the wheel 33 pushes the slider 82 outwards, the inclined surface 82^a thereon moves the bolt 81 out of engagement with the coupling half 80^c and the latter under 70 the action of the springs 80^d engages with the coupling half 80^a, whereby the auxiliary control shaft is driven by the continuously rotating worm wheel 12^a, the rotation continuing for one complete revolution only, 75 because after the passage of the cam 33^a past the nose 82^b of the slider 82 the latter is immediately retracted towards the axis of the machine by the springs 85 and thus permits the bolt 81 to move towards the coupling 85 half 80^c and disengage the coupling half 80^a when the inclined surface 82^b runs on to the bolt, thus uncoupling the shaft 12.

In the machine illustrated it is assumed 80 that the tools x with vertical feed consist say of roughing drills, finishing drills and reamers, while the tools y with horizontal feed consist say of roughing tools, form tools and cutting off tools. The vertical tools x are longitudinally movable in the 85 guide member 46 by the aid of their holders 43 and are also rotatable on their own axes in the opposite direction to the rotation transmitted from the main shaft 7 to the 90 work spindles 10, for which purpose the shaft 7 is coupled to the shafts 67 of the tool carriers 43 through toothed wheels 83. The carriers 44 of the horizontal tools y are carried in slides and are connected to the appropriate levers 43^b and 43^d by links 67^a. 95

Since the work pieces are arranged above the tools the turnings fall straight down. To divert any turnings thrown towards the centre of the machine by centrifugal force, a throw-off disc 87 is provided at a suitable 100 height on the main shaft 7.

The mode of operation of the above described machine is as follows, assuming that all work spindles are supplied with lengths of material, the tools selected in accordance 105 with the shape of the work pieces, for instance the hubs shown in Figure 11, it is desired to make, and their feeds properly adjusted.

The full working cycle of one work spindle will be considered from the point when the spindle has reached station I after a hub has been cut off from the rod material therein (Figures 2 and 5). While the auxiliary control shaft 12, which is coupled through 115 the coupling 80, 80^a and has effected the movement of the work spindle to the station I, is still rotating, a forward feed of the material z in the spindle takes place at 120 station I, through the agency of the rotation 125

of the shaft 12. This feed is rendered possible by the sliding sleeve 68 of the work spindle in question having come into engagement with the control sleeve 59 of the 5 grooved drum 58 driven from the auxiliary control shaft so that it must take part in the movement of this sleeve.

The sleeve 59 actuated by the drum 58 moves the sleeve 68 downwards and the lifting levers 70 are thus enabled to swing out 10 by centrifugal force (the spindle is rotating upon its own axis) so that the sleeve 74 supported thereby up till this instant and the tube 71 attached thereto together with 15 the collet 79 and the rod of material z can descend far enough to permit the collet 79, of which the conical head 79^a leaves its seat 72^a in the tube 72, to open and allow free descent of the material z until it reaches 20 the stop 65 which has in the meantime been swung into stopping position. At the same time the sleeve 76 also moves downwards, while the ring 77 remains supported by the pins 75 which results in the brake shoes 78 25 following the downward movement of the material being moved to brake the sinking material. The material thus automatically feeds itself forward by an amount which is limited to the length of the hub to be made 30 by the stop member 65. Directly this is completed the sliding sleeve 68 is raised by the action of the grooved drum 58, the lifting levers 70 are swung inwards, the sleeve 74 is slightly raised by the edges 70^a of the 35 levers 70 and therewith also the tube 71 with the collet 79 which now grips the material owing to its conical head 79^a being drawn into the slating 72^a of the tube 72, so that the stop 65 which is no longer needed to 40 support the material can swing laterally out of the way.

The tools which have to operate upon the work piece at station I and which up to this instant have been out of action, are now moved into their operating positions, the 45 still rotating auxiliary control shaft 12 through the cam 16 and the lever 17 having engaged the coupling 15, 18 to couple the worm 11^a driven by the shaft 3 with the shaft 13 and transmit the drive thence 50 through the wheels 19, shaft 21 and gears 24, 30 (Figures 3 and 5) to the tool feed shafts 31, 34, 35, the coupling half 80^a then running with its inclined surface 80^b on to the 55 bolt 81 which directly after the coupling has been engaged has again been released by the cam 33^a (Figure 9), whereby it is disengaged and the auxiliary control shaft 12 brought to rest. In this position the vertical 60 axial roughing drill x and a horizontally fed roughing tool y come into action. For explaining the movement of the tools reference is directed to the left hand side of Figure 5, it being at the same time pointed 65 out that the movements of the tools at all

six stations of the work spindles are similar. The feed of the vertical drill is effected by one of the feed cams 37 which through the linkage 42^a, 43^a first rapidly lifts the drill and then by a spiral portion 37^x slowly feeds 70 it up, while the drill is rotated through the respective wheels 86. The feed of the lateral roughing tool y is effected by one of the feed cams 38 which is similarly formed to the above mentioned cam 37 and first rapidly 75 feeds the tool into position through the linkage 42^b, 43^b, 67 and then feeds it slowly by a spiral portion 38^x. In this way axial boring and lateral turning of the work piece 80 are effected.

When this operation is complete, first the slider 82 is pushed back by the cam 33^a of the wheel 33 which receives its motion from the shaft 3 through the wheel 31^a, in order by withdrawing the bolt 81 to allow the 85 coupling half 80^a to engage the coupling half 80 thus setting the auxiliary control shaft 12 again in motion. The result is that after withdrawal of the revolver drum bolt 51, the revolver drum 9 is rotated through 60° 90 by the Maltese cross mechanism 52, 53, 54, carrying the work spindle in question with the roughed work piece to the station II (Figure 2), where a further operation thereon takes place. At this new station a 95 second drill and a second roughing tool come into action on the work piece in the spindle in question, under the feed of the cams 37^a, 38^a. A further step of the revolver drum brings the spindle to the station III (Figure 2), where say a third drill and a third roughing tool carry on the work, now under the feed of other cams 37 and 38. After this the spindle comes to station IV where say a larger drill and a form tool come into 100 action, then to station V where a finishing drill and finishing form tool effect the last stage in shaping the work piece, and finally to station VI where say a reamer and cutting off tool complete and part off the finished 105 work piece. Thus a work piece is obtained here say of the form shown in Figure 11, assuming that the drills and tools have the proper form and their feeds effected by the various feed cams adjusted to suit the work. 110 Finally the work spindle again reaches the station where a forward feed of the material takes place as described above.

What is described above for one work spindle naturally applies to the others which 115 one after another all pass through the stations described in accordance with the step by step movement of the revolver drum 9 carrying them, so that hubs as shown in Figure 11 are obtained as long as there is 120 sufficient material in the spindles and no change is made in the tools and their feeds. If a different profile is desired on the hub, or an altogether different work piece, the tools and feeds must be changed accordingly. 125 130

The automatic vertical feed of the material in Figure 5, while the feed motion is correspondingly controlled. For rotating the tool while in action it is driven from the shaft 7 through one gear, while its rotation out of action is effected through the other gear. Between the gears 92^a and 92^b is arranged a coupling 92 which can be coupled to either gear. The coupling is moved by a slider 93 carrying a pin 91 which engages in a grooved cam 90 on the swinging shaft 66 of the stop member 65 so that the movement of the shaft 66 with the stop member also changes over the coupling from the gear 92^b to the gear 92^a and vice versa through the cam 90.

5 feed forward of the material takes place without a feed chuck by simple descent of the material, and owing to the rotation of the spindles 10 on their own vertical axes, self centering of the material on the axis of 10 rotation is produced by centripetal force, the material then being gripped for working in a collet chuck. That the machine as described works rapidly and gives a large output is obvious. Owing to the self-centering 15 of the work pieces noiseless guiding thereof in the spindles takes place, since the rods themselves rotate without undesirable chattering movement. The ease of rotation of the revolver drum with the parts carried 20 thereby, owing to the support thereof on a ball bearing, increases the output capacity of the machine.

The vertical arrangement of the machine with vertical feed of the material decreases 25 the floor space required, which is usually more limited than the height available. The accessibility of the machine from all sides is a notable advantage particularly with the mounting of the parts on pillars in 30 place of in a closed frame. The turnings simply fall downwards; in addition to the throw-off disc 87 means can be provided to prevent the turnings getting into the driving gear of the machine. To carry away the 35 work pieces a runway can be provided.

Advantageously the revolver drum 9 is adjustable in height on the frame pillars of the machine; the same applies to the vertical axial tool holders and the horizontal guides 40 for the side tools. In this way the tools can be adjusted to suit the lengths of the work pieces to be machined.

If the work pieces do not require such extensive operations as described above and 45 a smaller number of tools suffice for machining them, the described machine can be provided, as indicated in Figure 12, with a second control mechanism 55', 58', 59' diametrically opposite the mechanism 55, 58, 59 so that with a smaller number of operations, the material is fed forward after half a rotation of the work spindles about the axis of the machine, and accordingly two work pieces completed at each step of the 55 machine. Naturally a second stop member to limit the feed of the material must then also be provided. In this way a double automatic machine is obtained.

With tools for screwing it may be advantageous to effect their rotation into and out of action by the aid of different relative speeds with respect to the material. For this purpose two gears 92^a, 92^b of different ratios for the rotation of the screwing tools 60 can be provided as indicated in dotted lines

always remains a main characteristic of the machine, as well as its axial positioning by means of the centripetal force. Indeed, the 5 feed forward of the material takes place without a feed chuck by simple descent of the material, and owing to the rotation of the spindles 10 on their own vertical axes, self centering of the material on the axis of 10 rotation is produced by centripetal force, the material then being gripped for working in a collet chuck. That the machine as described works rapidly and gives a large output is obvious. Owing to the self-centering 15 of the work pieces noiseless guiding thereof in the spindles takes place, since the rods themselves rotate without undesirable chattering movement. The ease of rotation of the revolver drum with the parts carried 20 thereby, owing to the support thereof on a ball bearing, increases the output capacity of the machine.

In the machine of the kind described it may happen that the work pieces are to be provided with bore holes, openings, slots or the like directed transversely to their axis. It is obvious that for such working, the work spindles cannot rotate upon their axis, but must be in position of rest. A construction that allows the work spindles to be brought at rest for this purpose is represented by Figures 13 and 14.

In this modification, a spring urged friction clutch is interposed between the spindle 10 and its driving wheel 10^a, this clutch comprising a conical hollow part 109 integral with the toothed wheel 10^a and a conical sliding sleeve 108 mounted on a jacket 110 of the spindle 10 and subjected to the action of a pressure spring 111 which tends to frictionally engage the sliding sleeve 108 with said hollow part 109.

In the centre of the revolver drum 9 there is arranged a vertical guide sleeve 100 provided with vertical guide slots 101 and engaged over the enlarged head part 103 of a fixed vertical rod 102, said head part being 105 provided with an annular groove 104 and a cam 105 projecting thereinto. The slots 101 serve as guides for controlling slides 106 corresponding in number to the working spindles 10 and which are arranged around the rod head part 103 and are so shaped that they engage by two fork arms 106^a into an annular groove 108^a of the coupling sleeves 108 for displacing same. The controlling slides 106 are each provided with a controlling pin 107 engaging the groove 104 and producing by its cooperation with the cam 105 the disengagement of the friction clutch.

The cam 105 is located at a certain predetermined point of the circular path and the sleeve 100 is connected by suitable means to the revolver drum 9 so as to partake of the intermittent rotary movement thereof on the head part 103 of the rod 102. When, in the rotary movement of the sleeve 100, the controlling pin 107 of a slide 106 runs on to the cam 105, the slide 106 is raised in its guide path and consequently the coupling sleeve 108 disengaged from the counter-part 110 115 120 125 130

109. The clutch is disengaged for the respective work spindle 10 and the same comes to rest, eventually with the aid of a suitable braking device. The work piece now at rest 5 can receive the transverse operation, whereupon, when the controlling pin 107 leaves the cam 105, the coupling is reengaged for the rotation of the work spindle. It results from the foregoing that, while five work 10 spindles, that is all that are not in the field of operation of the cam 105, rotate upon their own axes, the sixth always, the drive of which is disengaged by the cam 105, does not rotate about its axis.

15 15. It may be advantageous to render the controlling head 103 by means of its rod 102 adjustable in axial direction as well as in peripheral direction in order to withdraw its cam 105 from cooperation with the controlling pins 107 or to adjust it to another point around the axis of the machine.

What I claim is:

1. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a holder for said tools, a revolver drum coaxially arranged to said driving shaft and having bearings for said work piece spindles, a number of vertical frame columns distributed around said central shaft and arranged to support said revolver drum and said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rapidly rotate same upon their own axes at such a speed as to simultaneously produce an accurate axial setting of the work pieces within their holding spindles.

2. In an automatic lathe of the vertical type, the combination of a central main driving shaft, automatic means for driving same, a number of a rotary vertical work piece holding hollow spindles distributed around said central shaft, a number of operative tools distributed around said central shaft and located beneath said work piece spindles, an adjustable holder for said tools, 50 a revolver drum coaxially arranged to said driving shaft and having bearings for said work piece spindles, a number of vertical frame columns distributed around said central shaft and arranged to support said revolver drum and said tool holder, means for

rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rapidly rotate same upon their own axes at such a speed as to simultaneously produce an accurate axial setting of the work pieces within their holding spindles.

3. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a holder for said tools, a revolver drum coaxially arranged to said driving shaft and having bearings for said work piece spindles, a hollow carrier for said revolver drum, vertical frame columns distributed around said central shaft and arranged to support said revolver drum carrier and said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rapidly rotate same upon their own axes at such a speed as to simultaneously produce an accurate axial setting of the work pieces within their holding spindles.

4. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a holder for said tools, a revolver drum coaxially arranged to said driving shaft and having bearings for said work piece spindles, a hollow carrier for said revolver drum, vertical frame columns distributed around said central shaft and arranged to support said revolver drum carrier and said tool holder, means for rotating said revolver drum step by step to bring the work piece spindles successively into different working positions with respect to the tools, automatic feeding means on said work piece holding spindles to vertically feed the work pieces by a downward movement to the operative tools, a controlling device for said work

- piece feeding means, interconnecting means to establish an operative connection between said controlling device and said work piece feeding means one time at each revolution 5 of the spindles, and driving means between said central shaft and the work piece holding spindles enclosed within said hollow revolver drum carrier and so arranged as to rapidly rotate same upon their own axes 10 at such a speed as to simultaneously produce an accurate axial setting of the work pieces within their holding spindles.
5. In an automatic lathe of the vertical type, the combination of a central main driving shaft, automatic means for driving same, a number of rotary vertical work piece holding hollow spindles distributed around said central shaft, a number of operative tools distributed around said central shaft 15 and located beneath said work piece spindles, a common holder for said tools, a revolver drum coaxially arranged to said driving shaft and having bearings for said work piece spindles, a hollow carrier for said revolver drum, vertical frame columns distributed around said central shaft and arranged to support said revolver drum carrier and said tool holder, means for rotating said revolver drum step by step to bring the work piece spindles successively into different working positions with respect to the tools, automatic feeding means on said work piece holding spindles to vertically feed the work pieces by a downward movement to the operative tools, a common auxiliary control shaft for controlling said revolver drum advancing means and said work piece feeding means, a coupling device between said auxiliary control shaft and said main driving shaft for periodic actuation of said auxiliary control shaft, and driving means between said central shaft and the work piece holding spindles so arranged as to rotate same upon their own axes at a high speed for accurate axial setting of the work pieces within their holding spindles. 20
- 30 6. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a common tool holder, a number of vertical frame columns carrying said revolver drum with the work piece holding spindles as well as said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles.
- 35 7. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a common tool holder, a number of vertical frame columns carrying said revolver drum with the work piece holding spindles as well as said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles. 40
- 45 8. In automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a common tool holder, a number of vertical frame columns carrying said revolver drum with the work piece holding spindles as well as said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles. 50
- 55 9. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a common tool holder, a number of vertical frame columns carrying said revolver drum with the work piece holding spindles as well as said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles. 55
- 60 10. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a common tool holder, a number of vertical frame columns carrying said revolver drum with the work piece holding spindles as well as said tool holder, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles. 65

9. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a common holder for said tools, a revolver drum coaxially arranged to said driving shaft and having bearings for said work piece spindles, vertical frame columns to support said revolver drum and tool holder, a central drive for rotating the tools acting by rotation, a lever mechanism for advancing the tools to the working pieces, carried by said frame columns, a laterally arranged driving cam device for controlling said lever mechanism, said cam device being connected to the central main driving shaft, means for rotating said revolver drum step by step to bring the work piece spindles successively into different working positions with respect to the tools, automatic feeding means on said work piece holding spindles to vertically feed the work pieces by a downward movement to the operative tools, and driving means between said central shaft and the work piece holding spindles so arranged as to rotate same upon their own axes at a high speed for accurate axial setting of the work pieces within their holding spindles.

10. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a revolver drum coaxially arranged to said driving shaft and having bearings for said work piece spindles, a hollow carrier for said revolver drum extending around the set of the work piece spindles, a ball bearing on said carrier for said revolver drum, means for rotating the latter step by step to bring the work piece spindles successively into different working positions with respect to the tools, automatic feeding means on said work piece holding spindles to vertically feed the work pieces by a downward movement to the operative tools and driving means between said central shaft and the work piece holding spindles, enclosed within said hollow revolver drum carrier and so arranged as to rotate same upon their own axes at a high speed for accurate axial setting of the work pieces within their holding spindles.

11. In an automatic lathe of the vertical type, the combination of a central main driving shaft, automatic means for driving same, a number of rotary vertical work piece holding hollow spindles distributed

around said central shaft, a number of operative tools distributed around said central shaft and located beneath said work piece spindles, a revolver drum coaxially arranged to said driving shaft and having bearings for said work piece spindles, a Maltese cross plate rigidly connected to the revolver drum, having substantially the same diameter as the latter, a hollow carrier for said revolver drum extending around the set of work piece spindles, a ball bearing on said carrier for said Maltese cross plate, advancing means cooperating with the latter to bring the work piece spindles successively into different working positions with respect to the tools, automatic feeding means on said work piece holding to vertically feed the work pieces by a downward movement to the operative tools, and driving means between said central shaft and the work piece holding spindles, enclosed within said holder revolver drum carrier and so arranged as to rotate same upon their own axes at a high speed for accurate axial setting of the work pieces within their holding spindles.

12. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, automatic feeding means on said work piece holding spindles to vertically feed the work pieces by a downward movement to the operative tools, said feeding means comprising a tubular body, a slidable clamp sleeve therein for the working piece, hinged levers arranged to support said clamp sleeve and capable of swinging out under the action of the centrifugal force, a slidable control sleeve arranged to hold said levers in supporting position, means to periodically displace said control sleeve so as to allow said levers to swing out and consequently said clamp sleeve to free the working piece for its sinking down, and driving means between said central shaft and the work piece holding spindles so arranged as to rotate same upon their own axes at a high speed for accurate axial setting of the work pieces within their holding spindles.

13. In an automatic lathe of the vertical type, the combination of a central main driving shaft, automatic means for driving same, a number of rotary vertical work piece holding hollow spindles distributed around said central shaft, a number of operative tools distributed around said central shaft and located beneath said work piece spindles, a holder for said tools, drive mechanisms for actuating said tools with a different speeding ratio for the operative and the

return stroke thereof, a revolver drum coaxially arranged to said driving shaft and having bearings for said work piece spindles, vertical frame columns for supporting

5 said revolver drum and tool holder, means for rotating said revolver drum step by step to bring the work piece spindles successively into different working positions with respect to the tools, automatic feeding means on

10 said work piece holding spindles to vertically feed the work pieces by a downward movement to the operative tools, and driving means between said central shaft and the work piece holding spindles so arranged

15 as to rotate same upon their own axes at a high speed for accurate axial setting of the work pieces within their holding spindles.

14. In an automatic lathe of the vertical type, the combination of a central main

20 driving shaft, automatic means for driving same, a number of rotary vertical work piece holding hollow spindles distributed around said central shaft, a number of operative tools distributed around said central

25 shaft and located beneath said work piece spindles, a revolver drum coaxially arranged to said driving shaft and having bearings for said work piece spindles, means for rotating said revolver drum step by step to

30 bring the work piece spindles successively into different working positions with respect to the tools, automatic feeding means on said work piece holding spindles to vertically feed the work pieces by a downward

35 movement to the operative tools, driving means between said central shaft and the work piece holding spindles so arranged as to rotate same upon their own axes at a high speed for accurate axial setting of the work

40 pieces within their holding spindles, a coupling on each work piece holding spindle in combination with said driving means to allow disengagement thereof for a temporary stopping of the normal rotation of the work

45 piece holding spindle, and a central common control device for automatically controlling the coupling on the work piece holding spindles during the revolving path thereof.

In witness whereof I have hereunto
50 signed my name this 29th day of June 1931.

OTTO SCHÄFER.
